UNITED STATES PATENT OFFICE.

EMIL DE CLYNE, OF MOUNTAIN LAKES, NEW JERSEY.

TOY OR GAME.

1,324,386.

Specification of Letters Patent.

Patented Dec. 9, 1919.

Application filed January 28, 1918. Serial No. 214,148.

To all whom it may concern:

Be it known that I, EMIL DE CLYNE, a citizen of the United States, and a resident of Mountain Lakes, Morris county, State of New Jersey, have invented certain new and useful Improvements in Toys or Games, of which the following is a specification.

My invention relates to toys or games. It has for its object to produce a toy bowling game easily playable and yet requiring attention and skill. It consists of the novel devices and combinations herein set forth.

In the drawing accompanying this specification and forming part hereof, I have shown my improvement in its preferred form. Referring to such drawing, Figure 1 represents a perspective view of my improved bowling alley and bowling figure. Fig. 2 is a view of the bowling figure with its swinging arm retracted to the farthest backward position. Fig. 3 represents the same figure with the swinging arm in the act of throwing the ball. Fig. 4 is a view giving details of the swinging arm and its operating mechanism.

1 is a toy bowling alley of which 2 are the pins and 3 the bowling figure. The bowling figure is preferably made of metal of substantial weight, and with the feet spaced apart and arranged so as to be firmly planted when the figure is placed upon the alley, as shown in Fig. 1. The bowling figure is movable upon the alley so that it can be adjusted to give proper aim and direction to the ball. If desired, the figure may be held by the hand during the delivery of the ball. 4 is a swinging arm secured to and carried by a rod 5 mounted and turning in a circular opening or sleeve in a plate 24 secured to body 6 of the figure. The hand 7 of this arm is hollowed out so as to receive and hold the ball 8. In order to prevent the escape of the ball from the hand during the backward movement of the swinging arm, 45 and in the forward movement until the right point is reached for the ball to be thrown from the hand, I provide a retaining device adapted normally to project slightly into the hand, and I provide means for withdrawing such retaining device from its retaining position at the proper time. The device shown for the purpose consists of a swinging piece 9 pivoted at 10 to arm 4, and having a toe portion 11 which normally is held tilted to the right so as to project slightly into the hollow space of the hand.

A spring 12 pressing against the upper portion 13 of the retaining device 9, holds toe 11 in this position normally. The ball 8 can be pressed into the hollow hand forcing the toe 11 upward. Spring 12 and toe 11 thereupon hold the ball in position in the hand during the backward motion of the swinging arm.

The ball is released when the arm has 65 swung forward to its limit by means of portion 13 striking the pin 14 fast to and projecting from the left leg of the bowling figure.

In my improvement as shown I provide 70 means energized by the backward movement of the swinging arm which, when released, cause the swinging arm to be thrown forward, and I preferably provide means for varying the amount of energy thus imparted according to the wish of the player. As shown, the backward movement of arm 4 winds up a spring 15 secured at one end to plate 24 at 16, and at the other end, 17, secured to rod 5 of the swinging arm. The 80 amount to which this spring can be compressed is determined by a ratchet 18 pivoted to plate 24 at 19 and held normally toward the right, as shown in Figs. 2 and 3, by the spring 20, and a pawl 21 fast on rod 5. The ratchet 18 is provided with any desired number of teeth 22. As shown I have provided three.

The operation of the device is as follows: The player, after first placing the ball 8 in 90 the hollow of hand 7 where it is held by the toe 11, places the bowling figure in position at the end of the alley, as shown in Fig. 1, and swings the arm 4 back to any desired position, where it is held by means of pawl 95 and ratchet 21 and 18, depending upon whether the player desires to send a slow or a fast ball. This compresses spring 15 to the desired amount. The player then plants the bowling figure in proper position 100 to get the correct aim, and then pulls down ratchet 18, as indicated by the finger 23 in Fig. 1, holding the playing figure with his other hand, if desired. The pulling down of ratchet 18 releases spring 15, and the 105 latter swings arm 4 forward until part 13 of the retaining device strikes the pin 14, releasing the ball 8, causing the ball to be thrown from the hand down the alley.

Of course any suitable means for storing 110 energy may be used in place of the spring 15. My improved game affords great lati-

tude for skill both in placing the bowling figure properly and in adjusting the speed of the ball.

What I claim as new and desire to secure by Letters Patent, is:

1. In combination with a toy bowling alley and pins, a bowling figure provided with feet spaced apart, movable to any part of the alley and so arranged as to be firmly planted upon the alley and adapted to be moved into and held in position on the alley for purposes of aim, and provided with a swinging arm adapted to carry and throw the ball, whereby the aim will be dependent upon the skill of the player, and means for retaining said swinging arm in any one of a plurality of predetermined points.
2. In combination with a toy bowling alley and pins, a bowling figure having a swinging arm and hand adapted to carry and throw the ball, the combination of a retaining device adapted normally to project into the hand to prevent the escape of the ball therefrom, and means for withdrawing said device from its retaining position at the proper time in the forward movement of the swinging arm and hand, the swinging arm being provided with means for retaining it in any one of a plurality of predetermined points, to permit the discharge of the ball from the hand, said figure being movable to any part of the alley and adapted to be operated from any angle in relation to the pins.
3. In combination with a toy bowling alley and pins, a bowling figure having a swinging arm and hand adapted to carry and throw the ball from any one of a plurality of predetermined points in which it may be retained, the combination of a retaining device adapted normally to project into the hand to prevent the escape of the ball therefrom, a pin projecting from the figure into the path of the swinging arm and adapted to be struck by the retaining device at the proper time in the forward movement of the swinging arm to force said retaining device out of its retaining position to permit the discharge of the ball from the hand, said figure adapted to be placed on and operated from any position on the board and at any angle with relation to the pins.
4. In combination with a toy bowling alley and pins, a bowling figure having a swinging arm and hand adapted to carry and throw the ball from any one of a plurality of predetermined points, the combination of a retaining device, a spring adapted normally to force the retaining device slightly into the hollow of the hand to prevent the escape of the ball therefrom, and a pin projecting from the figure into the path of the swinging arm and adapted to be struck by the retaining device at the

proper time in the forward movement of the swinging arm to force said retaining device out of its retaining position to permit the discharge of the ball from the hand, said figure being adapted to be placed on and operated from any position on the board, and at any angle with relation to the pins.

5. The combination of a toy bowling figure provided with a swinging arm adapted to carry and throw the ball, means, adapted to be energized on the backward movement of the swinging arm, to cause the forward throwing movement of the swinging arm, and a device under the control of the player for varying the amount of energy thus imparted to the swinging arm to enable the speed of the ball to be varied.

6. The combination of a toy bowling figure provided with a swinging arm adapted to carry and throw the ball, a spring adapted to be energized on the backward movement of the swinging arm, and a tripping device under the control of the player for retaining the swinging arm at any one of a plurality of predetermined points in its backward movement, and for releasing it, to enable the speed of the ball to be varied.

7. The combination of a toy bowling figure provided with a swinging arm adapted to carry and throw the ball, a spring adapted to be energized on the backward movement of the swinging arm, a ratchet provided with teeth mounted on the body of the figure, and a retaining pawl mounted on the swinging arm and adapted to engage the ratchet and to be held in its backward position by any of the teeth of the ratchet.

8. A movable toy bowling figure provided with feet spaced apart and so as to be firmly planted in any desired position upon the alley, a swinging arm and hand pivoted on the body and adapted to carry and throw the ball, a spring mounted on the body and compressed when the swinging arm is moved backward, a catch for holding the swinging arm in its backward position adapted to be released by the player, a ratchet mounted on the body of the figure for holding the arm at a plurality of points in its backward movement so as to regulate the force of the forward swing, a hand adapted to hold the ball, a spring-pressed stop for holding the ball in the hand, and a pin, secured to the figure and adapted to be struck by said stop during the forward movement of the swinging arm, to release the ball, whereby the figure may be placed in position on the alley to give any desired aim, and the swinging arm, when retracted and released, will discharge the ball from the hand at the proper moment in the forward movement of the swinging arm.

In testimony whereof, I have signed my name to this specification.

EMIL DE CLYNE.
